BALL WHIRLING TOY

Harold Aster, 788 Sacco Place,
North Bellmore, N.Y. 11710

Filed Aug. 31, 1971, Ser. No. 176,778

Term of patent 14 years

Int. Cl. D21—01
U.S. Cl. D34—15 K

FIG. 1

FIG. 2

FIG. 3

FIG. 1 is a perspective view of a ball whirling toy, showing my new design;

FIG. 2 is a side elevational view thereof;

FIG. 3 is a bottom plan view thereof.

I claim:

The ornamental design for a ball whirling toy, substantially as shown.
